CLOCK

Gordon Florian, Bridgeport, Conn., assignor to Sunbeam Corporation, Chicago, Ill., a corporation of Illinois

Application December 31, 1956, Serial No. 44,355

Term of patent 14 years

(Cl. D42—7)

Fig. 1 is a front perspective view of a clock embodying my new design;

Fig. 2 is a top view of the clock shown in Fig. 1;

Fig. 3 is a side elevational view of the clock shown in Fig. 1 with the front part thereof being shown in cross section as seen along line 3—3 of Fig. 2.

The back of the clock is substantially plain.

I claim:

The ornamental design for a clock, as shown and described.
